DESIGN FOR A TENNIS SKIRT

Clara Mellen, New York, N. Y., assignor to The Jaeger Company Inc., New York, N. Y., a corporation of Delaware

Application February 26, 1938, Serial No. 75,429

Term of patent 3½ years

To all whom it may concern:

Be it known that I, Clara Mellen, a citizen of the United States of America, and residing at 620 Fifth Avenue, New York city, in the county of New York and State of New York, have invented a new, original, and ornamental Design for a Tennis Skirt, of which the following is a specification, reference being had to the accompanying drawing, forming part thereof.

I claim:

The ornamental design for a tennis skirt substantially as shown.

CLARA MELLEN.
